UNITED STATES PATENT OFFICE.

LORRAINE F. ANDRES, OF CINCINNATI, OHIO.

FILM-TRANSPORTING BOX.

Application filed May 5, 1921. Serial No. 466,984.

To all whom it may concern:

Be it known that I, LORRAINE F. ANDRES, a citizen of the United States, and a resident of Cincinnati, in the county of Hamilton and State of Ohio, have invented a Film-Transporting Box, of which the following is a full, clear, and exact description, reference being had to the accompanying drawings, forming part of this specification.

10 My invention relates to boxes used for transporting moving picture films from place to place and particularly to a method of supplying addresses in routing of films from one display point to another.

15 In the moving picture art the transportation of films is one of the greatest annoyances in connection with the theatrical end of the business. Each film is sent out from some agency for a number of displays or

20 showings usually at different theaters, after which the film is returned to the agency for repairs. The theaters advertise the arrivals of films on given days of the week, and if by any chance the prior user does not

25 promptly and correctly ship the box containing the film to the next user, there is likely to be a dark house. Labels are pasted on the boxes to give mailing directions and are either made out beforehand, and shipped in the boxes or left to the last user of the film to inscribe.

30 In practice the boxes are of metal and securely closed, and come back once every week or so to the distributing point for inspection and repairs. The boxes are used so many times that they become literally covered with pasted labels, sometimes in a large number of thicknesses, and it is easy for one user to insecurely paste on the box the label giving the address of the next user. It is also a frequent occurrence that the boxes get wet and the labels come loose, or where a number of old labels are mounted on top of each other, one of the bottom ones get loose thereby release the topmost one.

35 It is the object of my invention to provide a film box which has a special addressing means, which is foolproof to a large degree, and very safe from accidental loss of any of the labels.

40 This object I accomplish by that certain construction and arrangement of parts to be hereinafter more specifically pointed out and claimed.

In the drawings,

Figure 1 is a perspective view of the box showing the perforated lid.

Figure 2 is a perspective view of the filler block or board.

Figure 3 is a view of one of the address bearing plates.

The box selected for use with my invention is the usual moving picture film box, having sides 1, a base 2, handles 3 and a hinged lid 4.

A hole 4^a of desired size is cut in the lid 4, through which hole the address plate is visible. The lid itself fastens down over the loop 5, as in the usual film box. The flanges of the lid engage around the sides of the box, and the top of the lid is spaced away from the upper edge of the box when the lid is closed.

As a protection to the addressing plate, I preferably mount on the upper edges of the box a board or plate 6, which has a set of nobs or button-like projections 7 formed thereon. These nobs are formed in a pattern slightly larger or about the size of the pasted label which is used with the addressing plate.

The addressing plates 8 are made up of thin metal, or some other suitable material, which should preferably be imperishable and fit within the flanges of the lid resting on the plate 6 when it is used. In the center of the plates 8 usually on both sides thereof, are mounted pasted labels or addressing slips 9 upon which the mailing addresses are written by hand.

When a film box is sent out the film is deposited in the box and the plate 6 set on the upper edge of the box. The desired number of addressing plates are then made up with labels pasted thereon, giving the addresses to be used in routing the film. The lid is then closed down over the addressing plates and plate 6 and locked in place as is the usual practice.

If a film is to go to three theaters and then return to the distributing point, two plates will be used. The first plate will have the first and second addresses, and the second plate will have the third address and the return address to the distributing agency.

When the plates rest on the plate 6, the nobs thereon hold the addressing plates away from the plate 6, so that any moisture

or sweating on the top of the plate 6 will not come into contact with the label that is turned down, but will on the contrary be spaced away therefrom. The plate 6 also 5 protects the interior of the box from damage from moisture that might get in through the hole in the box lid.

The first user, when he is through with the film will scratch off his address label 10 and turn the plate over on which his label was pasted. This will give the next address for the film without chance of error. The second user will have to follow directions in getting the next addressing plate right side 15 up for the third user, although if he is careful to keep the plate the way it comes to him, this third address will be found to be on top. All address plates will be numbered before leaving the distributor.

20 The addressing plates will be of thin material, so that two or three of them can be inserted at once between the plate 6 and the lid of the box.

There will, of course, be various ways 25 of using the addressing plate and box, which accomplish the same objects as my invention in some mechanically equivalent way, and I wish to include such modification as within the scope of my invention.

30 Having thus described my invention, what I claim as new and desire to secure by Letters Patent, is:—

1. A container for photographic films and the like, comprising a box having a movable 35 lid provided with depending flanges, said lid having an aperture to expose an ad-

dressing tag, an independent plate adapted to seat on the top edges of the box and be covered by the lid and flanges, and an address bearing plate adapted to seat on the 40 plate first referred to and be enclosed between said plate and the lid and its flanges, said address bearing plate having carried thereon a label bearing an address.

2. A container for photographic films and the like, comprising a box having a movable lid provided with depending flanges, said lid having an aperture to expose an addressing tag, a plate adapted to seat on the box and be covered by the lid and flanges, and an address bearing plate adapted to seat on the 45 plate first referred to and be enclosed between said plate and the lid, said address bearing plate having carried thereon a label bearing an address, and said first mentioned plate having elevated portions thereon to preserve a spacing between it and the addressing plate, for the purpose described.

3. In a device of the character described, the combination with a metallic container, 50 a lid thereon having flanged sides and an apertured top, said lid being spaced away from the upper edges of the container, a plate seated over the edges of the container, and a thin plate mounted on the first mentioned plate, said last noted thin plate bearing address tags on its two faces adapted to be exposed through the aperture in the lid, said lid being adapted to clamp down the 55 various plates between it and the edges of the box, as and for the purpose described.

LORRAINE F. ANDRES.
